* cited by examiner

Primary Examiner — George D. Kirschbaum*Assistant Examiner* — CLese Moore, Jr.(74) *Attorney, Agent, or Firm* — Lambert & Associates; Gary E. Lambert; David J. Connaughton, Jr.(57) **CLAIM**

The ornamental design for the paddle, as shown and described.

DESCRIPTION

FIG. 1 is a perspective front view of the paddle, which embodies my design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown illustrate portions of the paddle that form no part of the claimed design.
